UNITED STATES PATENT OFFICE.

WILLIAM CLEMSON, OF MIDDLETOWN, NEW YORK.

IMPROVEMENT IN BUCK-SAW FRAMES.

Specification forming part of Letters Patent No. 123,556, dated February 13, 1872.

I, WILLIAM CLEMSON, of Middletown, in the county of Orange, in the State of New York, have made certain Improvements in Buck-Saw Frames, of which the following is a specification:

The object of this invention is to cheapen, and at the same time strengthen, the frame without increasing its weight or cost; and it consists in the construction and arrangement of the several parts that compose the frame, as will more fully hereinafter be described.

In the drawing, Figure 1 represents in side view the saw-frame and its several parts.

A is the hand-end of the frame. A' is the opposite end of the frame. B is the fulcrum-brace or cross-bar between the end pieces A and A'. C is the saw, one end of which is inserted in the end piece A', in the usual manner, and held by pin d, while the other end has a screw-rod, e, attached, and passes through end piece A, with a thumb-nut, e', thereon, and by which the saw is strained. b b are simple straight rods of metal wire, put into holes that go obliquely through the end pieces A and A', and through brace B. These rods b b go through the end pieces A and A', above the brace B, and thence obliquely through the brace B, as seen in Fig. 1, and are so inserted for the purpose of strengthening and stiffening the joint where the brace B enters the end pieces A and A'.

As will be seen, the joints made by the brace B and the end pieces A and A', are not affected by the straining of the saw by turning up the thumb-nut e' against the end piece A, for while thus contracting or forcing the end pieces toward each other, the oblique direction at which the rods b go through both the end pieces A and A' and brace or bar B prevents the opening of the joint on the upper side of the brace B, by reason of the rod b being clamped both in the end pieces and brace the moment the lower ends of the end pieces are made to approach each other, causing an upward deflection of the brace or bar B by the pulling

action of the rods b; consequently causing the frame to become rigid and unyielding, and in consequence of which condition the end pieces A and A' may be much smaller and lighter, and A' shorter, or not projecting so far above the strain-brace as A, as is the case in other constructions, which will reduce the expense of the frame in proportion as the wood is less.

This invention is an improvement upon the frame patented to me October 10, 1871, in which was used common wood screws to strengthen and hold the joints in contact, as in practice it is found that the screw is wholly unnecessary, as a simple plain piece of wire will answer every purpose of the screw, and being cheaper in its cost will necessarily cheapen the frame without in any way taking from it any of the advantages described in said patent, in which a screw is used; and by my present improvement, as herein described, I do away with the strain-rod at the upper end of the frame, that was necessary in the patent cited.

I am aware of the patent dated July 5, 1870, to E. M. Boynton, for a saw-frame, and I disclaim the construction therein shown, as the saw-frame in that patent is heavy and cumbersome, it having two cross-bars through which pass the diagonal rods before entering the end pieces. While in my frame there is but a single cross-bar, through which and the end pieces the diagonal rods go, while the lower end piece is much shorter, thereby making a lighter and better-balanced frame, as well as a much cheaper one.

Having thus described my invention, what I claim, and desire to secure by Letters Patent, is—

The combination of the end pieces A A', cross-bar B, and diagonal rods b b, constructed and arranged to form the frame of a buck-saw, as shown and described.

WM. CLEMSON.
